UNITED STATES PATENT OFFICE.

MICHAEL R. CAPUTO, OF SCRANTON, PENNSYLVANIA.

CROSSING GATE.

Application filed February 23, 1927. Serial No. 170,837.

This invention relates to railway safety devices and has especial reference to crossing gates, an object being to provide train controlled means for simultaneously moving 5 a pair of gates into position upon opposite sides of a railway track, so as to obstruct a crossing upon the approach of a train.

Another object of the invention is the provision of train controlled means for operating 10 a signal prior to the operation of the gates, so that persons approaching the crossing will be warned of the approach of a train before the gates are closed.

Another object of the invention is the provision of novel means for operating the gates and for guiding said gates during 15 their opening and closing operations.

With the above and other objects in view, the invention further includes the following 20 novel features and details of construction, to be hereinafter more fully described, illustrated in the accompanying drawings and pointed out in the appended claims.

In the drawings:

Figure 1 is a view showing a railway crossing illustrating in diagram the electric circuits.

Figure 2 is a plan view showing the arrangement of the gates upon each side of the 30 crossing, the railway tracks being omitted.

Figure 3 is an elevation of one of the gates.

Figure 4 is an end view of the same with the guide rails in section.

Figure 5 is a fragmentary view partly in section illustrating the train carried device and its manner of engagement with the track device.

Figure 6 is a fragmentary elevation showing 40 one end of the track device.

Figure 7 is an enlarged section taken on the line 7-7 of Figure 6.

Figure 8 is a similar view on the line 8-8 of Figure 5.

Figure 9 is an elevation partly broken away showing the shoe of the train carried device.

Figure 10 is a transverse section showing 50 a form of conduit or housing for the electric conductor wires or cables.

Referring to the drawings in detail where in like characters of reference denote corresponding parts, there is illustrated in Figure 11 a double track, one of which is indicated at A and the other at B, the train which moves over the track A moving in the

direction of the arrow a, while the train using the track B moves in the direction of the arrow b. The crossing is indicated at C. While two tracks are shown, the invention is equally useful in connection with a single track or with more than two tracks.

Positioned upon opposite sides of the tracks are spaced pairs of substantially U-shaped guide rails 10. These rails are arranged in pairs and their adjacent ends extend over the crossing as shown in Figure 2. These rails 10 are adapted to support and guide gates 11 which may be of the character illustrated in Figures 3 and 4 of the drawings. The gates are adapted to be operated in pairs, one gate of each pair being shown upon opposite sides of the railway track and at each side of the crossing C. The gates upon opposite sides of the crossing are adapted to be simultaneously moved into position to close the crossing and into position to open the crossing. The gates are supported upon rollers 12 which are arranged in pairs at each end of the gates and these rollers are mounted upon substantially U-shaped axles 13 which are carried by the gate frames. Positioned between these axles and extending longitudinally along the bottom of the gates are rack bars 14. These bars are engaged by pinions 15 and the latter are operatively associated with motors M, M¹, M² and M³, the arrangement being clearly illustrated in Figures 1 and 2 of the drawings.

Positioned upon opposite sides of the track at each side of the crossing are spaced pairs of track contacts P, P¹, P² and P³. In addition, there are provided spaced pairs of contacts P⁴ and P⁵ which are located upon opposite sides of the crossing. One of the contacts P is connected to one of the contacts P⁴ by means of a conductor 16, while one of the contacts P² is connected to one of the contacts P⁵ by a conductor 17. One of the contacts P is connected to one of the motors M by means of a conductor 18, while a conductor 19 which is tapped on to the conductor 18 connects with the other motor M. One of the contacts P⁴ connects with one side of the battery S by means of a conductor 20, while a conductor 21 leads from the other side of the battery to one of the contacts P. A conductor 22 leads from the first referred to motor M and to the battery by means of the conductor 20. A conductor 23 connects the conductor 22 with one of the contacts P¹.

A conductor 24 connects one side of the battery with one of the contacts P^5 while a conductor 25 connects one of the contacts P^2 with one of the motors M^2 and this motor has leading therefrom a conductor 26 which is tapped on to a conductor 27 leading from the conductor 22. This conductor 27 leads to a lamp 28 and leading from this lamp to the conductor 20 is a conductor 29. The motors M^1 are connected by a conductor 30 and one of the motors M and one of the motors M^1 connects with the conductor 27 by means of a conductor 31. A bell 32 is tapped on to the conductors 27 and 29 by means of conductors 33 and leading from one of these conductors to one of the contacts P^5 is a conductor 34. The motors M^2 are connected by means of a conductor 35 and the motors M^3 are connected by a conductor 36. A conductor 37 leads from one of the motors M^3 to one of the contacts P^3 , while a conductor 38 leads from one of the motors M^2-M^3 to the conductor 22. A conductor 39 connects one of the contacts P^1 with one of the motors M^1 and this motor is connected to the conductor 22 by means of a conductor 40.

The conductors or cables just described may be placed within a suitable conduit or housing such as is illustrated at 41 in Figure 10 of the drawings. This housing includes a removable cover 41^a and is provided upon its interior with separate channels 41^b which receive the conductors, the latter being indicated generally at 41^c.

The contacts $P-P^5$ are all of like construction and are illustrated in detail in Figures 5, 6 and 7 of the drawings. They include spaced rails 42 whose ends are beveled as at 43. These rails are connected by substantially U-shaped connecting bars 44 from which they are insulated as indicated at 45.

The rails are adapted to be engaged by a shoe indicated generally at 46 in Figure 9 of the drawings so as to bridge the rails and close a circuit through the motors. One of these shoes may be carried at each end of the train, or the train may carry a single shoe, the arrangement of the contacts being such that the circuits will be completed to close the gates before the train reaches the crossing and to open the gates after the train has passed. The shoe comprises a rigid bar 47 which is carried at the lower end of a right angular arm 48, while extending from the arm 47 near each end thereof are oppositely disposed headed studs 49. Contact members 50 are movable upon these studs and are yieldingly forced outward from the rigid bar 47 by means of springs 51. The leading ends of the members 50 are inturned as shown at 52 so that the shoe may conveniently enter the space between the rails or contact members 42. The arm 48 is carried by a cross-head 53 which operates in vertically disposed guides 54, the latter extending downwardly

from one of the cars of the train, a portion of a car is indicated at 55 in Figure 5 of the drawings. The crosshead guides are provided with a stop 56, while the crosshead carries an adjustable stop 57 which is adapted to engage the stop 56 to limit downward movement of the shoe 46 and by means of which the shoe may be accurately positioned to engage the contact rails 42. The crosshead 48 has connected thereto one end of a rod 58 and the opposite end of this rod is connected to a pivotally mounted hand lever 59. This lever is located within the car and carries a spring actuated latch indicated at 60 which is adapted to engage a toothed segment 61. By operating the lever 59, the shoe may be quickly moved into and out of position to engage the contact rails 42, so that if it is desired to render the gates inactive, the shoe may be elevated above the contact rails 42.

The operation of the invention is as follows:

A train approaching a crossing over the track A will first have its contact shoe 46 engaged with the contacts P^4 so as to bridge these contacts. Current from the battery S will then flow through the conductor 21, one of the contacts P , the conductor 16, the contacts P^1 , the conductor 20 back to the battery. As the lamp 28 and bell 32 are connected in parallel with the contacts through the conductors 27 and 29, the lamp will be lighted and the bell operated. At the same time, a lamp 28' which is connected in the conductor 20 will be lighted, while a bell 32' which is included in a shunt circuit 33' tapped on to the conductor 20 will also be operated. As soon as the shoe 46 leaves contacts P^4 , the circuit through the lamps and bells will be broken. Continued movement of the shoe will bridge the contacts P , so that current will flow from one side of the battery S through the conductor 21, the contacts P , the conductor 18, the motor M and back to the battery through the conductor 22. The other motor M is connected in parallel with the first mentioned motor by means of the conductors 19 and 27. Simultaneous operation of the motors M will thus be effected and the gates controlled by these motors will be moved to a closed position as shown in Figure 2 of the drawings. After the train passes the crossing, the shoe 46 will engage the contacts P^1 and current will flow from one side of the battery S through the conductor 21, the conductor 23, to the contacts P^1 , through the conductor 39 to one of the motors M^1 , through the conductor 40 to the conductor 22, the conductor 20 and back to the opposite side of the battery. The other motor M^1 is connected in parallel with the first referred to motor by the conductors 27 and 30. The motors M^1 will thus be simultaneously operated to open the gates.

A train moving in an opposite direction along track B will first bridge the contacts P⁵ to operate the signal devices 28—28' and 32—32' in the manner previously explained and will thereafter first close a circuit simultaneously through the motors M² to close the gates before the train reaches the crossing and to subsequently close a circuit through the motors M³ and open the gates.

10 The invention is susceptible of various changes in its form, proportions and minor details of construction and the right is herein reserved to make such changes as properly fall within the scope of the appended claims.

15 Having described the invention what is claimed is:—

1. In a safety device for railway crossings, gates mounted for movement upon opposite sides of the railway track and normally positioned at one side of the crossing, a pair of reversely operating motors associated with each gate, track contact members positioned upon opposite sides of the crossing and connected in circuit with the motors and with a 25 source of current and train carried means adapted to engage the contacts to operate the motors and move the gates to closed position as a train approaches the crossing and to thereafter return the gates to their normally open position.

2. In a safety device for railway crossings, a pair of horizontally movable gates normally located upon opposite sides of the railway track at each side of the crossing and 35 adapted to be moved into position to close the crossing, a pair of reversely operating motors associated with each gate, one of the

motors of each gate being connected in parallel with a source of current whereby each pair of gates will be simultaneously moved 40 in a given direction when a circuit is completed through the motors and train controlled means to successively close and open a pair of gates.

3. In a safety device for railway crossings, 45 a pair of horizontally movable gates normally located upon opposite sides of the railway track at each side of the crossing and adapted to be moved into position to close the crossing, a pair of reversely operating motors associated with each gate, one of the motors of each gate being connected in parallel with a source of current whereby each pair of gates will be simultaneously moved in a given direction when a circuit is 50 completed through the motors, signals also included in circuit with the motor and train controlled means to successively operate the signals and close and open a pair of gates.

4. In a safety device for railway crossings, 60 horizontally movable gates located upon opposite sides of a railway track and normally positioned at each side of the crossing, spaced U-shaped rails extending longitudinally upon each side of the track, gate carrying rollers 65 operating within the rails to guide the gates in their movement, rack bars extending longitudinally of the gates, pinions engaging the rack bars, reversely rotatable motors for operating the pinions and means to control 70 the motors to move the gates to closed and open positions.

In testimony whereof I affix my signature.
MICHAEL R. CAPUTO.
